UNITED STATES PATENT OFFICE.

LAURENCE E. TOPHAM, OF SWAMPSOCTT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

INSEAM SEWING-MACHINE.

1,289,314.

Specification of Letters Patent. Patented Dec. 31, 1918.

Application filed April 23, 1917. Serial No. 163,880.

To all whom it may concern:

Be it known that I, LAURENCE E. TOPHAM, a citizen of the United States, residing at Swampscott, in the county of Essex and State of Massachusetts, have invented certain new and useful Improvements in Inseam Sewing-Machines; and I do hereby declare the following to be a full, clear, and exact description of the invention, such as 10 will enable others skilled in the art to which it appertains to make and use the same.

The invention relates to inseam shoe sewing machines such as are used for sewing the uppers to the soles of turn shoes, or the 15 welts and uppers to the insoles of welt shoes.

In machines of this type as heretofore constructed the feed of the work has been intermittent, and consequently has involved starting and stopping the work during each 20 stitch forming cycle. These machines usually operate upon lasted shoes, and the inertia of the comparatively heavy last and shoe which must be overcome at the beginning and end of each feeding movement 25 limits the speed of operation, and subjects the feeding devices and the work to objectionable strains which are liable to injure the between substance and to cause inaccuracies or variations in the lengths of the 30 stitches. The rapidly recurrent intermittent feed also renders it difficult for the operator to properly hold and guide the work, particularly in operating about the toe or at points where the contour of the 35 shoe changes rapidly.

It is the object of the present invention to eliminate these objectionable features, thus permitting the speed of operation to be increased, and also permitting the work to be 40 more easily and accurately guided, and with less care and exertion on the part of the operator. To this end the invention contemplates so mounting and actuating some or all of the work engaging devices of the stitch 45 forming and work guiding mechanism that the work is advanced or fed continuously during the sewing, thus eliminating the objectionable strains and inaccuracies incident to starting and stopping the work during 50 each stitch forming cycle, and permitting the speed of the machine to be increased, and also facilitating the proper guiding and manipulation of the shoe by the operator. The specific form of the parts, and the man-

ner of mounting and relatively actuating them to continuously feed the work is not material to the broader scope of the invention. In embodying the invention in inseam sewing machines in which the channel guide reciprocates in the line of feed, either with or without a feed point or awl, it is preferred to mount the needle and back-gage to reciprocate together in the line of feed, and to so time the reciprocations that the return movement or back-feed of the needle and back-gage occurs during the forward feed of the channel guide or channel guide and awl while the back-feed of the latter part or parts occurs while the needle is in the work and is moved forward in the direction of the feed. The back rest with which machines of this type are usually provided may also be mounted to move in the direction of the feed, and when so mounted, is preferably advanced and returned in unison with the 75 needle.

The invention will be readily understood from an inspection of the accompanying drawings and the following detailed description of the machine illustrated therein. 80

In the drawings, Figure 1 is a right-hand side elevation of a welt and turn sewing machine embodying a preferred form of the invention; Fig. 2 is a detail view on line 2, Fig. 1; Fig. 3 is a detail section on line 3, 85 Fig. 1; Fig. 4 is a left-hand side elevation of the machine; Fig. 5 is a partial front elevation, certain parts being omitted to better show the parts behind them; and Fig. 6 is a detail side elevation illustrating the support for the needle and back gage. 90

In the drawings the invention is shown embodied in a welt and turn sewing machine which is similar in general construction to the machine shown and described in Patent 95 No. 1,108,560, August 25, 1914. This machine is provided with a curved hook needle 2, a looper 4, a thread arm 6, and awl 8, a channel guide 10, a back-gage 12, which, as shown also acts as a welt guide, a back rest 100 14, a takeup 16, and an auxiliary takeup 18, all of which are similar in construction to the corresponding parts in the machine of the patent, and all of which, with the exception of the needle, back-gage and back rest, 105 are or may be similarly mounted and operated.

In the machine of the patent the work

is intermittently fed by the awl and channel guide, which are mounted on a feed slide and are advanced to feed the work while the awl is engaged therewith and the channel 5 guide is pressed into the channel, and are returned or back-fed while the shoe is held from movement in the line of feed by the engagement of the needle therewith. In the machine shown the objectionable features of 10 this intermittent feed are eliminated by so mounting and actuating the needle, back-gage, channel guide and awl, that the advance or feed of the work is continuous during the sewing. To secure this result the 15 channel guide and awl are mounted on a feed slide 20 which has the same construction as the feed slide of the patent, and is reciprocated by a cam lever 22 engaging a feed cam 24 as in the machine of the patent. 20 The channel guide is secured upon a lever 26 which is pivoted on the feed slide, and is rocked at proper intervals through a cam lever 28 and rock shaft 30, as in the machine of the patent. The awl is secured in an awl 25 segment 32 pivotally mounted on the feed slide, and connected by a link 34 with a lever 36 also mounted on the feed slide and rocked at proper intervals by a cam lever 38, as in the machine of the patent. The 30 needle and back gage (welt guide) are also mounted for reciprocation in the line of feed, and are advanced in the direction of the feed during the back-feed of the feed slide, and are returned or back fed during 35 the advance of the feed slide. As shown, the needle is secured in a needle segment 40 which is pivotally mounted and guided on a supporting plate 42, and is connected by a link 44 with an actuating cam lever 46. 40 The ends of the link are connected with the cam lever and needle segment by ball joints, to permit the movement of the needle and needle segment in the line of feed. The back-gage or welt guide 12 is secured upon 45 an arm 48 which is pivoted upon a stud 50 secured in the supporting plate 42. The arm 48 is connected by a link 52 to a back-gage slide 54 which is operated and locked at proper intervals by mechanism fully described in the patent referred to. The link is connected with the back-gage slide and the arm carrying the back-gage by ball joints, to permit the movement of the back-gage in the line of feed. The support 42 for the 50 needle and back-gage is secured to a rod or stud 56 mounted to slide longitudinally in bearings in the machine frame, and also forming the supporting stud on which the feed slide 20 is mounted. The support 42 is also guided and retained in proper position by the engagement of the stud 50 with a bearing formed in the bracket 58 (Fig. 5). 55 The mechanism for reciprocating the stud 56, support 42, and the needle and back-gage 60 carried thereby, comprises a cam lever 65

pivoted at 62 to a fixed supporting bracket, and provided at its rear end with a roll 64 engaging the feed cam 24. The lever is connected to the rod 56 by a pivot stud 66 which is adjustably secured in a slot 68 in the lever 70 and engages a pivot block 70 which fits within a transverse slot in a block 72 formed on the end of the rod. By adjusting the stud 66 the movement of the needle and back-gage in the line of feed may be varied in accordance with the length of stitch to be sewed, and in accordance with the adjustment of the mechanism for reciprocating the feed slide 20. 75

In the construction shown the back rest is 80 mounted for movement back and forth in the line of feed. As shown, the back rest is secured on the forward end of a lever 74 which is pivotally supported on the forward end of the back rest slide 76, and is connected at 85 its rear end to a link 78, the other end of which is connected to an actuating lever 80. The lever 80 is rocked to reciprocate the back rest in the line of feed through a pivot block 82 which is mounted on the block 72 at the 90 end of the rod 56, and fits within a slot formed in the upper end of the lever. Through these connections the movement of the rod 56 reciprocates the back rest in unison with the needle and back gage. In doing certain classes of work, at least, it has been found desirable to retain the back rest 95 in fixed position, rather than to oscillate it in the line of feed, since its return movement when operating on shoes in which there are 100 rapid changes in the contour of the last along the line engaged by the back rest has a tendency to knock or displace the shoe. 105

The mode of operation and timing of the parts is as follows. During the forward stroke of the needle through the work the needle, the back gage, the awl and the channel guide are all moving in the direction of the feed. After the needle has completed its forward stroke, and while the looper and thread arm are acting, the channel guide is withdrawn and the channel guide and awl are back fed. They complete their back feed, start forward in the direction of the feed, and reengage the work just before the needle 115 clears the work on its back stroke. Immediately after the needle finishes its back stroke, the back gage is lifted away from the work, and the back feed of the needle and back gage takes place. At the end of the back 120 feed they start forward in the direction of the feed, and the back gage engages the work and is locked just before the needle reaches the work on its forward stroke. It will be seen that one or more of the work engaging 125 elements is in active engagement with the work, and is moving in the direction of the feed at all times during each cycle, and that the back feed of each element takes place while one or more of the other elements is 130

actively engaging and feeding the work, so that a continuous forward or feeding movement is imparted to the work during the sewing. In order to secure a uniform as well as a continuous feed, it is preferred to so time the actuating mechanisms that each of the work engaging elements is started forward in the direction of the feed and brought up to substantially the speed of the feed before it has a feeding engagement with the work. Thus the work is fed smoothly and continuously during the sewing, with a minimum strain upon the work engaging and feeding elements, so that uniform stitches may be sewed at an increased speed. The uniform and continuous movement of the work also enables the operator to more easily and accurately hold and guide the work, and relieves his arms of the constant vibration incident to the usual intermittent feed.

While it is preferred to employ the specific construction and arrangement of parts shown and described in embodying the invention in a machine having the general construction of the machine shown and described in the patent above referred to, it will be understood that this construction and arrangement is not essential to the broader features of the invention, and may be varied or modified as found desirable or best suited to the construction and arrangement of the parts of the machine in which it is to be embodied.

Having explained the nature and object of the invention, and specifically described one form of mechanism in which it may be embodied, what is claimed is:—

1. An inseam sewing machine, having, in combination, a needle, a back gage, a channel guide, and mechanism for actuating the same to continuously feed the work during the sewing.

2. An inseam sewing machine, having, in combination, a needle, a back gage, a channel guide, mechanism for advancing the needle in the direction of feed while in the work and for returning it while out of the work, and mechanism for actuating the back gage and channel guide to continue the feed while the needle is out of the work.

3. An inseam sewing machine, having, in combination, a needle mounted to reciprocate in the line of feed, a back gage mounted to reciprocate in the line of feed, and a channel guide cooperating with the needle and back gage to continuously feed the work during the sewing.

4. An inseam sewing machine, having, in combination, a needle, a back gage and a channel guide all mounted to reciprocate in the line of feed, and mechanism for relatively actuating them to continuously feed the work during the sewing.

5. An inseam sewing machine, having, in combination, a needle, a back gage, a chan-

nel guide and an awl, all mounted to reciprocate in the line of feed, and mechanism for relatively actuating them to continuously feed the work during the sewing.

6. An inseam sewing machine, having, in combination, a support mounted to reciprocate in the line of feed, a needle and a back gage mounted on the support, a slide mounted to reciprocate in the line of feed, a channel guide mounted on the slide, and mechanisms for reciprocating the support and slide timed to alternately back feed them.

7. An inseam sewing machine, having, in combination, a support mounted to reciprocate in the line of feed, a needle and a back gage mounted on the support, a slide mounted to reciprocate in the line of feed, a channel guide and an awl mounted on the slide, and mechanisms for reciprocating the support and slide timed to alternately back feed them.

8. An inseam sewing machine, having, in combination, a needle, a back gage, a channel guide, mechanism for actuating the same to continuously feed the work, and a back rest movable in the line of feed and movable toward and from the work.

9. An inseam sewing machine, having, in combination, a needle, a back-gage and a channel guide all mounted to reciprocate in the line of feed, and mechanism for moving each part in the direction opposite to that of the feed during the movement of one or more of the other parts in the direction of the feed.

10. An inseam sewing machine, having, in combination, stitch forming and work guiding mechanism including a needle and channel guide, and mechanism for actuating work engaging devices of the stitch forming and work guiding mechanism to continuously feed the work during the sewing.

11. An inseam sewing machine, having, in combination, stitch forming and work guiding mechanism including a needle and channel guide and mechanism for actuating work engaging devices of the stitch forming and work guiding mechanism to continuously feed the work during the sewing timed to initiate the feeding action of each feeding device while some other device is still feeding.

12. An inseam sewing machine, having, in combination, stitch forming and work guiding mechanism including a needle and channel guide, and mechanism for moving one or more of the work engaging devices of the stitch forming and work guiding mechanism in the direction of feed throughout the sewing.

13. An inseam sewing machine, having, in combination, stitch forming and work guiding mechanism including a needle and channel guide, mechanism for moving the needle in the direction of feed while in the

work, and in the opposite direction while withdrawn from the work, and mechanism for actuating one or more of the other work engaging devices of the stitch forming and 5 work guiding mechanism to continue the feed while the needle is out of the work.

14. An inseam sewing machine, having, in combination, stitch forming and work guiding mechanism including a needle and 10 channel guide, mechanism for moving the needle in the direction of the feed while in the work, and in the opposite direction while withdrawn from the work, and mechanism

for moving one or more of the other work engaging devices of the stitch forming and 15 work guiding mechanism in the direction of the feed while the needle is out of the work.

15. An inseam sewing machine, having, in combination; a needle, channel guide and back gage, one or more of which is in active 20 engagement with the work throughout the sewing, and mechanism for moving each in the direction of the feed when in active engagement with the work.

LAURENCE E. TOPHAM.
